CLAIM

The ornamental design for a translucent placemat, as shown and described.

DESCRIPTION

FIG. 1 is a front perspective view of the translucent placemat of the present invention in a closed position.

FIG. 2 is a top view of the translucent placemat of the present invention in a closed position.

FIG. 3 is a bottom view of the translucent placemat of the present invention in a closed position.

FIG. 4 is a elevation view of the translucent placemat of the present invention in a closed position.

FIG. 5 is the opposite elevation view of the translucent placemat of the present invention in a closed position.

FIG. 6 is a bottom end view of the translucent placemat of the present invention in a closed position.

FIG. 7 is a top end view of the translucent placemat of the present invention in a closed position.

FIG. 8 is a top view of the translucent placemat of the present invention in an open position with a representative paper insert extending therefrom; and,

FIG. 9 is a perspective top view of the translucent placemat of the present invention with a representative paper insert extending therefrom.

The representative paper inserts do not form a part of this invention.

The broken line showing of the paper insert and pen is included for the purpose of illustrating use and environment and forms no part of the claimed design.
